(57) **CLAIM**

The ornamental design for a light emitting wheel hub, as shown and described.

DESCRIPTION

FIG. 1 is front elevation view of a light emitting wheel hub showing my new design. The design consist of two printed circuit plates with a transparent cover, the top cover being removed for clarity of illustration;

FIG. 2 is a rear elevation view of the light emitting wheel hub shown in FIG. 1;

FIG. 3 is a side elevation view of the light emitting wheel hub shown in FIG. 1, the opposing side elevation view being a mirror image thereof;

FIG. 4 is an enlarged and partial top plan view of the light emitting wheel hub shown in FIG. 1;

FIG. 5 is a bottom elevation view of the light emitting wheel hub shown in FIG. 1;

FIG. 6 is an enlarged front elevation view of the printed circuit plate in isolation and removed from the light emitting wheel hub shown in FIG. 1;

FIG. 7 is an enlarged rear elevation view of printed circuit plate shown in FIG. 6;

FIG. 8 is an enlarged perspective view of a typical cover for the light emitting wheel hub shown in FIG. 1;

FIG. 9 is an enlarged and partial from view of the light emitting wheel hub taken along portion 9-9 as shown in FIG. 1; and,

FIG. 10 is a perspective view of the light emitting wheel hub shown in FIG. 1.

The broken lines shown in the drawings illustrate portions of the light emitting wheel hub that forms no part of the claimed design.
